UNITED STATES PATENT OFFICE.

LEONARD STANLEY HINKS, OF KNOWLE, ENGLAND.

INTERNAL-COMBUSTION ENGINE.

1,294,102.

Specification of Letters Patent. Patented Feb. 11, 1919.

Application filed May 28, 1918. Serial No. 237,117.

To all whom it may concern:

Be it known that I, LEONARD STANLEY HINKS, subject of the King of Great Britain, residing at "Limpsfield," Widney Road, 5 Knowle, in the county of Warwick, England, have invented certain new and useful Improvements in Internal-Combustion Engines, of which the following is a specification.

10 The invention provides an internal combustion engine constructed and arranged to work in the manner hereinafter described and specifically claimed.

Said engine operates on the well known 15 four cycle principle, and constructionally provides an inner explosion cylinder and an outer explosion ring-like cylinder permanently closed to each other at their rear ends so that their explosion chambers at said rear 20 ends are quite independent. Said cylinders are concentrically arranged. Two sets of valves are provided for admission and exhaust, one set to each cylinder. An explosion piston is fitted to each cylinder, the outer 25 one being a ring-like piston. By a common connecting rod both pistons are coupled to the same crank shaft. The cycle of operations combined with the construction, aforesaid, is that the pistons alternately make 30 power strokes, the engine therefore giving an impulse for each revolution of the crank shaft.

The invention is represented by the accompanying sheets of drawings which show 35 an air cooled engine.

Figure 1 is a vertical section.

Fig. 2 is a plan of the upper end of Fig. 1.

Fig. 3 is a vertical sectional elevation at right angles to Fig. 1.

40 Within the one casing, *a*, is provided an inner cylinder, *a*², and an outer cylinder, *a*³, whose respective rear ends provide explosion chambers, *a*⁴, *a*⁵. These cylinders are concentric and open to each other within the 45 front *c* of the casing, but are closed to each other at the rear ends so that there is no communication whatever between the two explosion chambers, *a*⁴, *a*⁵. The inner cylinder, *a*², is an ordinary one, but the outer 50 cylinder, *a*³, is of ring or annular formation. The explosion chamber, *a*⁴, extends upwardly beyond the explosion chamber *a*⁵ for more efficient cooling of said cylinder. The front end *c* of the casing *a* fits within

the crank case *x* at the part *c*², to which 55 crank case the cylinder casing is securely bolted in substantially the ordinary way.

Independent sparking plugs are fitted to the explosion chambers, *a*⁴, *a*⁵, the screw threaded hole to receive one of them being 60 represented at *y* in Fig. 1.

Within the cylinder *a*² works a piston *e* coupled at *e*² to the crank of the crank shaft *e*³ by a connecting rod *f*, which, at *f*², engages the gudgeon pin of said piston in the 65 ordinary manner.

Rigidly attached to a flange *e*⁴ at the forward end of the piston *e* is the forward end *g*² of an annular or ring-like piston, *g*, fitted to work within the cylinder *a*³. This piston 70 is fitted with double sets of rings, *g*³, so as to make gas-tight joint with both outer and inner concentric surfaces, *a*⁶, *a*⁷, of the outer cylinder *a*³. Both pistons *e* and *g*, by being coupled at *e*⁴, constitute, in effect, a single 75 piston member having two piston portions but adapted to reciprocate as one piece, the common connecting rod *f* connecting said piston member as a whole to the crank shaft *e*³. The effective areas of the ends of the 80 pistons *e* and *g* are equal, as also are the areas of the explosion chambers *a*⁴, *a*⁵, which are separately fed and exhausted by two sets of valves, *h*, *h*², and *i*, *i*². Said valves *h*, *h*² and *i*, *i*² operate in valve pockets formed in 85 the casing *a* and communicating with the explosion chambers *a*⁵ and *a*⁴, respectively. The inner cylinder *a*² and inner piston *e* extend upwardly or outwardly beyond the outer cylinder *a*³ and outer piston *g* (see 90 Figs. 1 and 2), and the communicating valve pockets are correspondingly positioned, so that, while all of the valve pockets are located adjacent one another, the pockets for the valves *i*, *i*² are offset longitudinally of 95 the cylinders from the pockets for the valves *h*, *h*², as shown in Fig. 3, the pockets of the two sets being also laterally offset, as shown in Fig. 2.

The construction and operation of said 100 valves are well known, but it may be pointed out that *h*² is an inlet valve to the explosion chamber *a*⁵, and *h* is an exhaust valve from said chamber leading to the exhaust outlet *h*³, while *i* is an inlet valve to the explosion 105 chamber *a*⁴, and *i*² is an exhaust valve from said chamber, which two sets of valves are timed for lifting by the cams *j* and *m* by

any convenient timing gear driven from the crank shaft e^3 to drive the cam shafts j^2 m^2 . Said valves are automatically closed by pressure of coiled springs encircling the respective valve stems between abutments in the usual way but not shown in the drawings, it being sufficient for the purpose of the invention to indicate that two sets of independent valves suitably timed and operated 10 are provided one set for each cylinder to give the necessary cycle of operations which is as follows:—

While the inner piston e makes its power stroke the outer piston g is making its suction stroke: while said inner piston exhausts the outer piston compresses: while the inner piston makes its suction stroke the outer piston makes its power stroke, and while the inner piston compresses the outer piston 20 exhausts.

For the purpose of lifting the valves, h , h^2 , from the cams j , j^2 , the usual lifting rods h^4 , h^5 , are provided, working through sleeves h^6 h^7 fitted to the crank case x , and it is to be understood that two similar rods and sleeves 25 are fitted to the crank case to work the valves i i^2 from the cams m m^2 , all of which features are well known in gas engine practice.

For purposes of lubricating the two pistons e and g from the crank case x , the piston e is slotted at s , and the piston g is drilled through with a number of holes such as s^2 , which holes lead from a ring groove, s^3 , in said piston to a ring-like oil cup or pocket 30 s^4 , provided by the lower part of the space between the two pistons, into which cup or pocket the dividing wall, s^5 , between the two cylinders dips each time the pistons move rearwardly, with the object of facilitating 35 a splashing of lubricant upwardly within the inner cylinder a^2 . To aid splashing in the crank case the counter-weighted parts o of the crank shaft are toothed as at o^2 .

By reason of the fact that the inner piston 40 e extends beyond the outer piston g , bringing the explosion spaces of the corresponding cylinders into different longitudinal positions, the heat of the explosions is distributed over a considerable space, making it 45 possible adequately to cool the cylinders by means of the usual radiating fins, as shown, or otherwise. Such adequate cooling is not possible in constructions in which the inner piston is wholly within the outer piston. 50 Notwithstanding, however, the rearward extension of the inner piston, the latter is adequately lubricated from the crank case, through the slots s , holes s^2 , ring groove s^3 , and oil cup s^4 , by the splash action of the 55 dividing wall s^5 .

Having now described my invention what I claim and desire to secure by Letters Patent is:—

1. An internal combustion engine comprising an inner cylinder, an outer annular

cylinder surrounding said inner cylinder, a piston member having a piston portion in each of said cylinders, said piston member having an oil pocket between said piston portions and an oil opening communicating 70 with said pocket, the lower edge of the dividing wall between said cylinders entering said pocket, a crank case adapted to contain lubricant and with which the opening in said piston communicates, a piston rod connected to said piston member, and a crank shaft journaled in said crank case and having provision for splashing lubricant from said crank case upon said piston member.

2. An internal combustion engine comprising an inner cylinder, an outer annular cylinder surrounding said inner cylinder, a piston member having a piston portion in each of said cylinders, said inner cylinder and the piston portion therein extending beyond the outer cylinder and piston portion, said piston member having an oil pocket between said piston portions and an oil opening communicating with said pocket, the lower edge of the dividing wall between 85 said cylinders entering said pocket, a crank case adapted to contain lubricant and with which the opening in said piston communicates, a piston rod connected to said piston member, and a crank shaft journaled in said 90 crank case and having provision for splashing lubricant from said crank case upon said piston member.

3. An internal combustion engine comprising an inner cylinder, an outer annular cylinder surrounding said inner cylinder, a piston member having a piston portion in each of said cylinders, said piston member having an oil pocket between said piston portions, the inner piston portion having 100 slots communicating with said pocket, the outer piston portion having an exterior ring groove and an opening leading from said groove to said pocket, and the lower edge of the dividing wall between said cylinders 110 entering said pocket, a crank case adapted to contain lubricant, a piston rod connected to said piston member, and a crank shaft journaled in said crank case and having provision for splashing lubricant from 115 said crank case upon said piston member.

4. An internal combustion engine comprising an inner cylinder, an outer annular cylinder surrounding said inner cylinder, a piston member having a piston portion in 120 each of said cylinders, said inner cylinder and the piston portion therein extending beyond the outer cylinder and piston portion, said piston member having an oil pocket between said piston portions, the inner piston portion having 125 slots communicating with said pocket, the outer piston portion having an exterior ring groove and an opening leading from said groove to said pocket, and the lower edge of the dividing wall between said 130

cylinders entering said pocket, a crank case adapted to contain lubricant, a piston rod connected to said piston member, and a crank shaft journaled in said crank case and having provision for splashing lubricant from said crank case upon said piston member.

In testimony whereof I have hereunto set my hand in presence of two subscribing witnesses.

LEONARD STANLEY HINKS.
